Geo. B. Barrett's design for Paper Weights
5202

PATENTED AUG 15 1871

Witnesses.

John M. [unclear]
G. H. [unclear]

Inventor
Geo. B. Barrett

UNITED STATES PATENT OFFICE.

GEORGE B. GARRETT, OF PHILADELPHIA, PENNSYLVANIA.

DESIGN FOR A PAPER-WEIGHT.

Specification forming part of Design No. 5,202, dated August 15, 1871.

To all whom it may concern:

Be it known that I, GEORGE B. GARRETT, of Philadelphia, in the county of Philadelphia and State of Pennsylvania, have invented and produced a new and original Design for Paper-Weights, of which the following is a specification:

The nature of my design is fully represented in the accompanying photographic illustrations, to which reference is made.

I claim as my invention—

The design for a paper-weight, as shown.
GEO. B. GARRETT.
